FOUNTAIN FOR BIRDS

Patrick T. Flynn, Newark, N. J.

Application August 11, 1954, Serial No. 31,818

Term of patent 3½ years

(Cl. D31—2)

Fig. 1.

Fig. 2.

Fig. 3.

Fig. 1 is a side elevational view of a fountain for birds embodying my new design. Fig. 2 is a vertical sectional view taken on line 2—2 of Fig. 3 and Fig. 3 is a top plan view thereof.

I claim:

The ornamental design for a fountain for birds, as shown.
